INVENTOR.

Louis C. Vanderlip.

UNITED STATES PATENT OFFICE.

LOUIS C. VANDERLIP, OF ELKHART, INDIANA.

CONVEYER-ELBOW.

1,246,189.

Specification of Letters Patent. Patented Nov. 13, 1917.

Application filed April 26, 1916. Serial No. 93,587.

To all whom it may concern:

Be it known that I, LOUIS C. VANDERLIP, a citizen of the United States, residing at Elkhart, county of Elkhart, and State of Indiana, have invented new and useful Improvements in Conveyer-Elbows, of which the following is a specification.

This invention relates to pneumatic conveyers for the conveyance of ashes, sand, and other abrasive and disintegrated materials, and more especially to the conveyer conduit elbow carrying the nozzle for the introduction of steam or fluid under pressure to the conveyer conduit interior.

15 An object of the invention is the effectual and complete protection of the suction elbow against wear by the use of improved tubular wear liners. A further object is the provision of improved means to enable the ready 20 replacement of worn wear liners without the removal of the elbow itself from the conduit line. A still further object is the production of an elbow having an apertured wear liner through which the fluid under pressure is introduced. Other objects will be mentioned 25 and described herein from time to time.

The preferred embodiment of the invention is disclosed in the accompanying drawings, wherein Figure 1 is a longitudinal section in elevation; Fig. 2 is a section on the line 2-2 of Fig. 1; Fig. 3 is a view in side elevation of the cover plate in reduced size; Fig. 4 is a side view of the elbow showing all wear liners and the cover plate removed; 35 and Fig. 5 is a section showing a slight modification.

Similar numerals refer to similar members and parts of members throughout the several views on the drawings.

40 Referring to the drawings in detail, the numeral 1 indicates the elbow body provided with intake and discharge openings 2 and 3, respectively, the former having the conventional flange 4. The numeral 5 indicates a 45 wear liner insertion opening formed in the side of the elbow body and extending from a point therein adjacent the intake flange 4 around the elbow bend to a point intermediate the elbow bend terminus and the discharge opening 2. The opening 5 is normally divided into the bend portion 6 and the straight portion 7, the latter being somewhat larger diametrically than the portion 6. The numeral 8 indicates the lateral flange 55 of the insertion opening 5, substantially co-

extensive therewith and provided with the flat face, or surface, 9 and the bolt holes 10, 10. The numeral 11 indicates a cover plate for sealing the opening 5 and adapted to be held in position against the face 9 by the 60 bolts 12, 12 detachably engaging the flange 8.

The numeral 13 indicates a boss formed at the bend of the elbow exterior substantially midway thereof and provided with a nozzle aperture 14 which is substantially in axial 65 alignment with the discharge opening 3. The numeral 15 indicates a nozzle for fluid under pressure, preferably steam, rigidly but detachably arranged within the aperture 14, having its issuing end substantially in 70 axial alignment with discharge opening 3, and connected with a pipe 16 leading to a source of steam supply.

The numeral 17 indicates a tubular removable wear liner arranged within the elbow bend at the intake 2 and extending for a fraction of the bend length to the end of the removable tubular medial liner 18, the latter covering substantially the balance of the elbow bend length. The numeral 19 indicates an inlet aperture formed in the outer wall of the tubular liner 18 and in registry with the boss aperture 14 to permit the steam blast from the nozzle 15 to enter the elbow interior. The numerals 20 and 21 80 indicate tubular wear liners removably arranged within the elbow enlargement and forward of the bend terminus, each of which is somewhat thicker than the liner members 17 and 18. To accommodate liner member 90 21 the elbow extension bore is diametrically substantially the same as the enlargement 7. In operation, the liners 20 and 21 take the impact of the steam blast and the abrasive action of the materials cast or projected by 95 the steam before the latter is blown out of the discharge opening 3, thereby causing excessive wear within the longitudinal limits of said wear liners. For this reason, it is desirable to thicken the liners 20 and 21 to 100 prolong their period of service.

To house the wear liners within the elbow the liner 17 is inserted through the opening 6 and projected into position. The liner 18 is then placed in position, as shown, with 105 the inlet aperture 19 in registry with the aperture 14. The liner 21 may then be inserted and projected forward into the discharge opening 3, thereby permitting the subsequent insertion of the liner 20. To re- 110

tain the liners in position, after fastening the cover plate 11 in position, the plate 11 is provided with a projection 22, or a series thereof for each wear liner, each of which 5 engages a liner. It is obvious that other means may be resorted to for this accomplishment, such as a set screw, or the like. At Fig. 5 a plain unapertured liner 18 is shown for use when the elbow is utilized 10 merely as a lined elbow and without the nozzle 15.

I claim:

1. In combination with an elbow having a branch opening and an aperture in the 15 elbow bend, of an apertured wear liner removably arranged within the elbow and having its aperture in registration with the elbow bend aperture; and a detachable cover plate sealing said branch opening.
2. In a device of the class described, an 20 elbow provided with an aperture at its bend; an extension member connected with said elbow and provided with a branch opening; a wear liner removably arranged within 25 said extension; and a detachable cover plate sealing said branch opening.
3. The combination with an elbow having a branch opening and an aperture in the 28 elbow bend, of an apertured tubular wear liner removably arranged within the elbow and having its aperture in registration with the elbow bend aperture; and a detachable cover plate sealing said branch opening.
4. The combination with an elbow pro- 35 vided with a branch opening, of a wear lining removably arranged within the elbow and composed of a plurality of tubular sec- 40 tions arranged end to end and forming a continuous wear lining substantially coex- 45 tensive with the limits of the elbow bend; and a detachable cover plate sealing said branch opening.
5. The combination with an elbow pro- 50 vided with an extension and a branch open- 55 ing, the bend of said elbow being apertured, of an apertured wear lining removably arranged within the elbow bend, the aperture of said wear lining being in registration with said elbow bend aperture; another 60 wear lining removably arranged within said elbow extension; and a detachable cover plate sealing said branch opening.
6. In an elbow having bores of different 65 diameters and apertured at its bend, the 70 combination of a wear lining removably arranged within one elbow bore and having an aperture in registration with said elbow 75 aperture; and a wear lining removably

arranged within the other elbow bore and end to end with the other wear lining.

60

7. In a device of the class described, an elbow having a branch opening; an elbow extension carried by said elbow and provided with a branch opening; a wear liner removably arranged within said elbow; a 65 second wear liner removably arranged within the elbow extension; and a detachable cover plate sealing said branch openings.

8. The combination with an elbow pro- 70 vided with a lateral opening, of a tubular wear lining removably arranged within said elbow and extending partially around the elbow bend; a second tubular wear lining removably arranged within said elbow and coöperating with the other lining; and a 75 cover plate detachably fastened over said elbow lateral opening.

9. In a device of the class described, an elbow having a branch opening; an elbow extension carried by said elbow and provided 80 with a branch opening; a tubular wear liner removably arranged within said elbow; a second tubular wear liner removably arranged within said elbow extension and coöperating with said elbow liner; and a de- 85 tachable cover plate sealing said branch openings.

10. In a device of the class described, an elbow provided with a branch opening; an elbow extension carried by said elbow and 90 provided with a branch opening; a wear liner removably arranged within said elbow; a tubular wear liner removably arranged within said extension and coöperating with the elbow liner, said extension liner being 95 thicker than said elbow liner; and a detachable cover plate sealing said branch openings.

11. In a device of the class described, an elbow; an elbow extension provided with a 100 branch opening; a tubular wear liner removably arranged within said extension; and a detachable cover sealing said branch opening.

12. In a device of the class described, an 105 elbow provided with a branch opening; an elbow extension carried by said elbow; a wear liner removably arranged within said elbow; a wear liner removably arranged within said elbow extension; and a detachable cover sealing said elbow branch opening.

In testimony whereof I have hereunto affixed my signature this 24th day of April, 1916.

LOUIS C. VANDERLIP.
